UNITED STATES PATENT OFFICE.

LEE C. SHARP, OF PLATTSMOUTH, NEBRASKA, ASSIGNOR TO AMERICAN CAN COMPANY, OF NEW YORK, N. Y., A CORPORATION OF NEW JERSEY.

CAN-HEAD-SEAMING MACHINE.

1,094,937.

Specification of Letters Patent. Patented Apr. 28, 1914.

Application filed October 12, 1909. Serial No. 522,347.

To all whom it may concern:

Be it known that I, LEE C. SHARP, a citizen of the United States, and a resident of Plattsouth, in the county of Cass and 5 State of Nebraska, have invented certain new and useful Improvements in Can-Head-Seaming Machines, of which the following is a specification.

My invention relates to machines for 10 making sheet-metal cans in which the can-heads are secured upon the bodies by double-seaming or similar processes.

It is the object of my invention to provide 15 a simple and efficient machine for automatically applying and seaming the heads of cans upon the bodies thereof, in which by simple and easily operated adjusting means the machine may be adapted to operate upon cans of various lengths and diameters.

20 Further objects of my invention are to provide certain specific improvements in the means for feeding the can-bodies and heads to the seaming devices, in the means for actuating the seaming devices, and in the 25 various adjusting means for adapting the machine for use in making cans of different sizes.

Constructions embodying my invention are illustrated in the accompanying drawings, in which—

Figure 1 is a rear elevation of the machine, Fig. 2 is a detail plan view of the head-stock, Fig. 3 is a transverse vertical section on the plane of the line $x-x$ of 35 Fig. 1, Fig. 4 is a detail vertical longitudinal section of the head-stock, Fig. 5 is a transverse section of the feed-chute, Fig. 6 is a detail longitudinal section through one of the pockets of the carrier-wheel, and Fig. 7 is an enlarged detail sectional view showing the method of adjustably retaining one of the plates 17 on the shaft 12.

In the machine shown in the drawings, I provide a frame consisting of the horizontal 45 bed-plate or beam 1 supported by legs 2 and carrying at one end a head-stock 3, at the central part a tail-stock 4 and at the other end a bearing-standard 5. The head-stock 3 and bearing-standard 5 are fixedly secured 50 upon the bed, while the tail-stock 4 is mounted upon ways so as to be longitudinally slidable and is secured in adjusted position upon the bed by means of a bolt 6 passed through a slot in the bed. The main 55 driving shaft 7 is journaled in bearings

formed at the upper extremities of the standard 5, and of the tail-stock and head-stock, as shown. The said shaft carries a driving pulley 8 at the end adjoining the standard 5, and at the other end a short crank 9 is secured thereon. From said crank a rod 10 extends downwardly and is connected with one end of an arm 11 rotatably mounted on the carrier-wheel shaft 12 which is journaled in the lower portions of the head-stock and tail-stock, as shown. Said arm 11 carries a pawl 13 adapted to engage a ratchet wheel 14 secured on the end of the shaft 12. Between the bearings in the head-stock a brake-wheel 15 is secured on the shaft 12, said wheel having an adjustable brake-band extending around the same and connected with the head-stock. On the shaft 12 between the head-stock and tail-stock are mounted the carrier-plates 16 and 17. The plate 16 is fixedly secured on the shaft adjoining the head-stock, and the plate 17 is adjustable longitudinally upon the shaft, being connected therewith and held in adjusted position thereon by means of a feather 17^a and set-screw 17^b. Each of the plates 16 and 17 has equally spaced in the periphery thereof circular recesses in which the semi-annular bushings 18 are removably secured by means of the screws 19, as shown in Fig. 6. The said semi-annular bushings have on the inner faces thereof grooves adapted to receive the flanges *a* of the can-bodies *A*, the grooves in the bushings carried by the plate 16 being wide enough to receive also the cam-heads *B*, as indicated in Fig. 6. The carrier-wheel formed by the bushings 18 and the plates 16 and 17 may be adapted for handling cans of different diameters by changing the bushings for others having the proper bore to receive the cans to be handled, and by adjusting the plate 17 longitudinally upon the shaft the carrier-wheel may be adapted for handling cans of different lengths.

The can-bodies and heads are automatically fed to the carrier-wheel by means of an inclined chute which is supported on a bracket 20 arranged at the front side of the machine. The chute comprises the cross-bars 21 upon which the inclined bars 22 and 23, carrying the side-plates 24, are adjustably secured by means of screws which extend through slots in the cross-bars and are provided at their lower ends with thumb-

5 nuts 25, as shown in Fig. 5. The bars 22 and the side-plates carried thereby form a runway for the can-bodies A, and a narrow runway for the can-heads B is formed between the side-plate carried by the bar 23 and the adjoining side of the body-runway. The outer end of the chute is pivotally connected with the bracket 20, and the inner end of the chute is supported by the screw-10 studs 26 which are provided with adjusting nuts, as shown, by which the position of the lower end of the chute may be regulated to correspond with the stopping position of the adjoining carrier-pocket formed by the 15 bushings 18.

The carrier-wheel shaft 12 is intermittently actuated, by means of the ratchet connections described, in a direction such that the carrier-wheel will move upwardly at the 20 side thereof adjoining the feed-chute, and said actuating mechanism is so arranged that at each movement of the carrier-wheel one of the pockets therein will stop at the feed-chute, receive a can-body and head 25 therefrom, and at the next two successive movements of the wheel carry said can-body and head into the two operating positions between the chuck-plates 27. The said chuck-plates 27 are removably secured on 30 the inner ends of horizontal spindles 28 journaled in the head-stock and tail-stock in horizontal alinement with the two upper pockets of the carrier-wheel. On the outer ends of said chuck-spindles are pulleys 29 35 from which the spindles may be continuously driven by belts extending, preferably, to driving pulleys arranged on a shaft above the machine, one belt being used to drive both of the head-stock spindles and one to 40 drive both of the tail-stock spindles. The two pairs of spindles are simultaneously given intermittent longitudinal movements toward and away from each other by means of cams 30 and 31 carried on the main driving 45 shaft 7 above the head-stock and tail-stock, respectively. The said cams are engaged by rollers carried on the upper ends of the levers 32, the said levers at their lower ends extending between the chuck-spindles and having T-heads thereon, each 50 end of which engages a ring arranged in a groove-collar 33 carried by each of the spindles. Springs 34 engage the lower ends of the levers to press the same normally outward and keep the rollers in engagement 55 with the cams. The cam 31 is adjustable longitudinally of the driving shaft, being secured thereon by means of a feather and set-screw. 60 On the inner face of the head-stock above the chuck-spindles a plate 35 is slidably mounted in vertically-extending guides. On the back of the said plate is a lug through which is passed an adjusting-screw 36 which engages 65 a spring 37 arranged as shown in Fig. 4.

On the face of the plate is a roller 38 which said spring 37 normally holds in engagement with a cam 39 secured on the driving shaft 7, the said cam being adapted to impart an intermittent vertical reciprocating movement to the plate 35. A plate 40, at the lower end of which are mounted the seaming-rollers 41, is secured on the face of the plate 35 by means of screws 42 extending through vertical slots near the sides of said plate 40. The upward thrust from the seaming rollers upon the plate 40 is received by screws 43 which are passed through lugs projecting from the face of the plate 35, and by means of said screws and the screws 42 the vertical relation of the two plates which form the seaming-head may be so adjusted that when the plate 35 is pushed downwardly by the cam 39 the seaming-rollers will be brought into proper operating relation with the can-bodies and heads in the two upper pockets of the carrier-wheel. 70

The various operating elements are so timed with relation to each other that the operation of the machine is as follows: A can-body and head having been deposited by the feed-chute in one of the pockets of the carrier-wheel, as before described, the next movement of the wheel carries them between the first pair of chuck-plates, where 75 they remain during the return movement of the driving-pawl 13, the carrier-wheel shaft being held stationary by the friction of the brake-band upon the wheel 15. While in said position the chuck-plates and spindles are moved inwardly so that the chuck-plates 90 engage and force the can-body and head into contact with each other, at the same time imparting thereto a rapid rotary movement during which the respective seaming-roller 95 100 105 110 115 120 125 130 135 140 145 150 155 160 165 170 175 180 185 190 195 200 205 210 215 220 225 230 235 240 245 length but of different diameters it is necessary to change the bushings 18 of the carrier-wheel and change the chuck-plates 27 for others of the proper size for the cans to be handled, to adjust the position of the seaming-head plate 40, and raise or lower slightly the inner end of the feed-chute. In addition to the above it may sometimes be necessary to vary slightly the width of the 10 head-runway of the feed-chute, in order to accommodate therein can-heads having flanges or embossing of different depths.

Now, having described my invention, what I claim and desire to secure by Letters Patent is:

1. In a can head-seaming machine, the combination with seaming devices, of a carrier-wheel revolvably mounted on a horizontal axis and having peripheral pockets 20 adapted to receive and carry can-bodies and heads; a chute for feeding can-bodies and heads to the carrier-wheel; and chuck-plates mounted adjacent to the carrier-wheel and adapted to engage and rotate the cans in 25 proximity to the seaming devices; portions of the carrier-wheel, of the feed-chute, and of the means carrying the chuck-plates being adjustable axially of the carrier-wheel to adapt the machine for operating upon 30 cans of different lengths.

2. In a can head-seaming machine, a carrier-wheel mounted on a horizontal axis, means for feeding can-bodies and heads to said carrier-wheel, chuck-plates arranged in 35 pairs at opposite sides of the carrier-wheel, means for intermittently actuating the wheel to carry the cans between the successive pairs of chuck-plates, means for simultaneously actuating the chuck-plates to engage 40 the same with the cans, means for revolving the chuck-plates, seaming devices having a fixed relation with each other adapted to simultaneously engage a plurality of adjacent cans held by the chuck-plates, and 45 means for actuating said seaming devices synchronously with the carrier-wheel and chuck-plates.

3. In a can head-seaming machine, conveying devices adapted to receive and carry 50 cylindrical can-bodies and heads so that the axes thereof are substantially horizontal, can end engaging means rotatable on horizontal axes and arranged adjoining the conveying devices, means for actuating said

rotatable means to simultaneously engage 55 the same with a plurality of the can-bodies and heads, a vertically reciprocating head arranged above the rotatable means, a plurality of seaming-rollers carried by said head, and means for actuating said head 60 to simultaneously engage the seaming-rollers with a plurality of adjacent cans held by the rotatable means.

4. In a can head-seaming machine, a carrier-wheel mounted on a horizontal axis 65 having removable peripheral members containing pockets adapted to receive can-bodies and heads, means for intermittently actuating said carrier-wheel, a seaming-head, means for intermittently reciprocating said head toward and away from the carrier-wheel, seaming-rollers carried by the head, said seaming rollers being adjacent to each other and adapted to simultaneously engage adjacent cans on said carrier wheel and means on the head for adjusting the position of the seaming-rollers relative to the carrier-wheel to adapt the seaming head for operating upon cans of different diameters.

5. In a head-seaming machine for cylindrical cans, a feed-chute having inclined runways through which the can-bodies and heads may roll, means for adjusting the width of said runways, a plurality of seaming devices, pairs of rotating elements arranged adjacent to each of the seaming devices, conveying devices adapted to receive the cans from the feed-chute and carry the same successively to positions adjoining the seaming devices and between the pairs of rotating elements, means for adjusting the width of the conveying devices, means for adjusting the average distance between the pairs of rotating elements, 95 means for simultaneously moving each pair of rotating elements toward and away from each other, and means for simultaneously engaging all the seaming devices with the cans.

In testimony whereof I have hereunto subscribed my name in the presence of two witnesses.

LEE C. SHARP.
